UNITED STATES PATENT OFFICE.

CHARLES O. SEAMAN, OF DES MOINES, IOWA.

DESIGN FOR A WHISK-BROOM AND BRUSH HOLDER.

40,567.

Specification for Design.

Patented Mar. 8, 1910.

Application filed December 20, 1909. Serial No. 534,216. Term of patent 3½ years.

To all whom it may concern:

Be it known that I, CHARLES O. SEAMAN, a citizen of the United States, residing at Des Moines, in the county of Polk and State of Iowa, have invented a new, original, and ornamental Design for Whisk-Broom and Brush Holders, of which the following is a specification, reference being had to the accompanying drawing, forming part thereof.

The figure is a perspective view of the

whisk broom and brush holder showing my new design.

I claim:

The ornamental design for a whisk broom and brush holder as shown.

Des Moines, Iowa, Dec. 6, 1909.

CHARLES O. SEAMAN.
